UNITED STATES PATENT OFFICE.

WILBERT W. WILEY, OF ELMIRA, NEW YORK.

ARTICLE OF FURNITURE.

1,201,903.

Specification of Letters Patent. Patented Oct. 17, 1916.

Application filed March 10, 1916. Serial No. 83,331.

To all whom it may concern:

Be it known that I, WILBERT W. WILEY, a citizen of the United States, residing at Elmira, in the county of Chemung and State 5 of New York, have invented certain new and useful Improvements in Articles of Furniture, of which the following is a specification.

My invention relates to an improved article of furniture, namely a washstand, and the object is to provide a folding, portable washstand, which can be placed in a trunk, if need be, and carried about. And a further object is to provide an ornamental article of furniture, which may not only be used for a washstand, but also as a seat or settee, it being made uniform so that it is an ornamental piece of furniture, not even suggesting from its appearance its primary 20 purpose.

With these objects in view, this invention consists in a stationary top having a recess to receive a removable basin, with depending sides which conceal and house the basin 25 from the sides, a removable cover, hinged legs, and a hinged door or bottom which substantially closes the lower side, and when the legs are folded outward for the support of the article it serves as a means of 30 bracing with a wedging action against them to hold them firmly in place, to give rigidity to the device, and prevent its wobbling or collapsing under one's weight.

It further consists in certain other details 35 of construction, which will be hereinafter more fully described and set forth in the claims.

In the accompanying drawings:—Figure 1 is a top plan view; Fig. 2 is a bottom plan 40 view; Fig. 3 is a side view when folded; Fig. 4 is a vertical longitudinal section; Fig. 5 is a horizontal sectional view looking upward; and Figs. 6 and 7 are sectional details.

45 A, is the top having a countersunk opening 1 formed therein of a size and shape to receive the removable wash-basin 2, the flange 3 of which rests in the countersink of the opening 1, and recesses 4, 4, are formed preferably at the ends of the opening 1 to receive the fingers whereby the wash-basin is removed.

50 A removable cover 5 is adapted to fit over the stationary top 1, entirely covering and concealing the basin, it preferably having spring-friction-catches 6 at the edges, or

ends, or both, which enter slots 7 in the stationary top to hold the removable cover removably in place.

Depending for several inches from the 60 lower surface of the stationary top is the rectangular frame 8, which forms a housing for the support of the folding legs 9, 9, the hinged door or bottom 10, and the other parts, thereby forming a housing for concealing the basin, and a means of coöperating 65 with the other parts mentioned and to be mentioned, for not only supporting and concealing but also bracing the folding hinged legs which are nested therein when 70 folded against the lower surface of the stationary top, which are supported and braced with the coöperation of the hinged bottom or door when the legs are projected or folded outwardly for the support of the device. 75

The legs 9, four in number, are hinged or pivoted at opposite ends, either between the sides of the depending frame and blocks 11, 11, or between blocks 11 and 12 on rods 13, which extend across from side to side of the 80 frame, and through the block and legs, thus having the double function of holding the sides of the frame rigidly together, assisting in holding the blocks in place, and also forming means for hinging the legs in place. 85 The legs are preferably square in cross-section, and of uniform dimensions for a distance substantially corresponding to the width of the frame 8, and thence taper slightly to their extreme ends for several 90 reasons:—first, to give them a better appearance; second, to make them nest together more perfectly when folded; and third, and above all, to facilitate the closing of the hinged bottom or door 10, which in that way 95 is provided more clearance between the legs when closed, and by crowding against the thicker portions of the legs when closed having a wedging and bracing effect, thus forcing them outwardly against the frame A, 100 and holding them against side swing or vibration. A spring-catch 14 holds this hinged door or bottom in position when closed, and when thus closed and the legs are folded, it forms a flat article of furniture, folded in compact space, which may be packed in a trunk or stored elsewhere, on a shelf, or limited space. This hinged door bottom conceals the parts therebeneath, and more particularly the removable basin.

110 Thus when in use, with the removable cover in place, and the hinged bottom or

door closed, the device presents an attractive article of furniture, and may be utilized as a seat, settee, table, flower-stand, or what not.

5 The device is simple and of few parts, and can be made at a comparatively small initial cost. It is light and attractive in appearance, and can be utilized for various purposes, as has been specified, as well as 10 many other purposes too numerous to mention.

I claim:

1. A folding portable article of furniture comprising a stationary top having an opening therein, a basin removably secured in the opening, a removable cover, a frame depending from the lower surface of the top, spaced blocks secured vertically in the frame, rods extending through the blocks 20 and sides of the frame for holding the latter rigidly together, legs pivoted or hinged on

these rods between blocks and between blocks and sides of the frame, and a hinged door or bottom which fits between the legs when extended, forcing the latter against the 25 ends of the frame and holding them rigidly in place when projected, and means for securing the hinged bottom or door in position.

2. The combination with a top, a depending frame secured thereto, and tapering hinged folding legs, of a bottom or door hinged to the frame, and of dimensions to easily swing into the wider clearance provided at the outer ends of the legs by reason 35 of their taper, and adapted to crowd with a wedging action against the legs as the bottom or door is closed, whereby to form a rigid lateral inside support for the legs.

In testimony whereof I affix my signature. 40

WILBERT W. WILEY.
